DRESS

Harry Lang, St. Paul, Minn.

Application September 11, 1952, Serial No. 309,050

1 Claim. (Cl. 2—75)

1

The invention herein presents a new and improved dress, of character especially suitable to be worn by children while at play, consisting of several pieces of material providing a skirt and a bib of the dress, a band member, partially elastic material as disclosed, encircling an upper extremity of the skirt where it is joined to the bib, and adjustable shoulder straps connected between upper extremities of separate pieces of the bib at the front of the dress and spaced parts of said upper extremity of the skirt at the center of the rear of said dress.

In the accompanying drawings forming a part of this specification,

Fig. 1 is a front elevational view of a dress incorporating features and characteristics of the invention;

Fig. 2 is a detail sectional view, taken on line 2—2 in Fig. 1;

Fig. 3 is a rear elevational view of the dress; and

Fig. 4 is a detail sectional view, taken on line 4—4 in Fig. 3.

A skirt 10 of the dress is provided by six separate longitudinally extending pieces of material, two of which pieces, denoted 11 and 12, respectively, are at the front of said dress, and four of which pieces, represented 13, 14, 15 and 16, respectively, are at the rear of the dress. The adjacent marginal edges of the front longitudinally extending pieces 11 and 12 are connected at the center of the front of the dress by a vertical seam 17, the adjacent marginal edges of the rear longitudinally extending pieces 14 and 15 are connected at the center of the rear of said dress by a vertical seam 18, the adjacent marginal edges of the longitudinally extending pieces 13 and 14 are connected by a vertical seam 19 midway between the vertical seam 18 and a vertical seam 20 connecting the adjacent marginal edges of the longitudinally extending pieces 12 and 13, and the adjacent marginal edges of the longitudinally extending pieces 15 and 16 are connected by a vertical seam 21 midway between the vertical seam 18 and a vertical seam 22 connecting the adjacent marginal edges of the longitudinally extending pieces 11 and 16. The vertical seams 20 and 22 are at the center of the opposite sides of the dress, equally spaced from the front and rear thereof, and each of the longitudinally extending pieces 11, 12, 13, 14, 15, 16 of material is of divergent configuration in downward direction.

A bib 23 of the dress is provided by two longitudinally extending pieces, denoted 24 and 25,

respectively, of material, one of which is alined with the longitudinally extending piece 11 of the skirt and the other of which is alined with the longitudinally extending piece 12 of said skirt.

6 A band member 26, including elastic material 27 at the rear thereof in the disclosure as made, encircles the upper marginal edge of the skirt 10 at the location where the bib pieces 24 and 25 and said upper marginal skirt edge meet and are joined. The band member 26 and the lower marginal edge portions of the bib pieces 24 and 25 are stitched, as at 28, in substantially flatwise fashion to upper marginal edge portions of the longitudinally extending pieces 11 and 12 along substantially the full widths of said bib pieces and said pieces 11 and 12, and the elastic material 27 of the band member is stitched, as at 29, to upper marginal edge portions of the longitudinally extending pieces 13, 14, 15, 16 in such manner that said last mentioned upper marginal edge portions are puckered or shirred, as at 30, at locations disposed rearwardly of the dress.

15 Adjacent marginal edges of the bib pieces 24 and 25, as well as adjacent marginal edges of upper portions of the longitudinally extending pieces 11 and 12 with which said bib pieces are joined, are detachably connected by a vertical zipper 31 at the center of the front of the dress. 20 The vertical zipper 31 extends downwardly from the upper end of the line of meeting between the bib pieces 24 and 25 to position below the band member 26 and considerably above the lower edge of the skirt 10, and the lower end of said vertical zipper terminates at the upper end of the vertical seam 17.

25 The bib pieces 24 and 25 taper upwardly from their line of meeting at the vertical zipper 31. Adjustable shoulder straps 32 are connected, as 30 between upper extremities of the bib pieces 24 and 25 at the front of the dress and spaced parts 34 of the upper extremities of the longitudinally extending pieces 14 and 15 at opposite sides of and equally spaced from the vertical seam 18 at the center of the rear of said dress. 35 Stated otherwise, the spaced parts 34 to which the adjustable shoulder straps 32 are secured are situated along the length of the stitching 29. A cross piece 35 extends between the adjustable shoulder straps 32 at the rear of the dress at about the elevation of upper portions of the tapered parts of the bib pieces 24 and 25.

40 The dress is loose fitting, and the construction and arrangement, including the band member 26 and its elastic material part 27, and the

45 50 55

manner in which said elastic material part is assembled with the longitudinally extending pieces 13, 14, 15, 16, gives the desired shape to the garment. The "take-up" at and adjacent to the waist line, rearwardly of the dress and at opposite sides of the vertical seam 18, and the tapering configuration of the longitudinally extending pieces 11, 12, 13, 14, 15, 16 leave the front of said dress without folds and impart shape to the skirt rendering the dress pleasing in appearance. 10

What is claimed is:

A dress comprising a skirt consisting of a pair of downwardly diverging, longitudinally extending pieces at the front of the dress and four downwardly diverging, longitudinally extending pieces at the rear of said dress, vertical seams interconnecting all of said downwardly diverging, longitudinally extending pieces of said skirt, there being a first vertical seam at the center of the front of the skirt, a second vertical seam at the center of the rear of said skirt, third and fourth vertical seams midway between said first and second vertical seams at opposite sides of the skirt and fifth and sixth vertical seams midway between the second vertical seam and said third and fourth vertical seams, respectively, a bib consisting of a pair of longitudinally extending pieces constituted as upper continuations of said longitudinally extending pieces at the front of said dress, each of said longitudinally extending pieces of said bib including a first longitudi- 20 30

nal side edge having an upper concave portion and a lower straight portion at the inner side of the bib and a second longitudinal side edge of curvilinear configuration at the outer side of said bib extending substantially to the upper extremities of the longitudinally extending pieces of said skirt, said straight lower portions of the longitudinally extending pieces of said bib and upper central portions of said longitudinally extending pieces of the skirt at the front of the dress being detachably connected to form a front closure extending downwardly from the top of said garment, and shoulder straps connected between upper extremities of said longitudinally extending pieces of said bib at the front of said dress and a part of the dress at the center of the rear thereof at the elevation of upper extremities of the longitudinally extending pieces of said skirt.

HARRY LANG.
